175,720

KITCHEN IMPLEMENT

Samuel L. Gerson, Wilmington, Del.

Application January 7, 1955, Serial No. 33,867

Term of patent 14 years

(Cl. D11—1)

Fig. 1 is a side view of a kitchen implement showing my new design, and

Fig. 2 is a bottom edge view of the implement.

I claim:

The ornamental design for a kitchen implement, substantially as shown.

References Cited in the file of this patent

UNITED STATES PATENTS

D. 164,311	Mills	Aug. 21, 1951
D. 169,843	Gerson	June 16, 1953
1,097,171	Dalton	May 19, 1914